JUG

David G. Hills, Collierville, Conn., assignor to Monsanto Company, St. Louis, Mo., a corporation of Delaware

Filed Dec. 30, 1968, Ser. No. 15,144

Term of patent 14 years

Int. Cl. D9—01

U.S. Cl. D9—41

FIG. I

FIG. IV

FIG. II

FIG. III

I claim:

The ornamental design for a jug, as shown.
